No. 37,291.

Patented January 10, 1905.

UNITED STATES PATENT OFFICE.

JAMES C. ATKINSON, OF NEW YORK, N. Y.

DESIGN FOR FRINGE.

SPECIFICATION forming part of Design No. 37,291, dated January 10, 1905.

Application filed December 15, 1904. Serial No. 237,035. Term of patent 3½ years.

To all whom it may concern:

Be it known that I, JAMES C. ATKINSON, a citizen of the United States, and a resident of the city of New York, borough of Brooklyn, 5 in the county of Kings and State of New York, have invented a new, original, and ornamental Design for Fringe, reference being had to the accompanying drawing, in which the figure is a plan showing my new design for a fringe.

I claim as new and desire to secure by Letters Patent—

The ornamental design for a fringe herein shown.

JAMES C. ATKINSON.
